UNITED STATES PATENT OFFICE.

EDGAR S. GARDNER, OF ACQUACKANONCK, NEW JERSEY, ASSIGNOR TO GENERAL ELECTRIC COMPANY, A CORPORATION OF NEW YORK.

FILAMENT-MOUNTING.

1,001,630.

Specification of Letters Patent. Patented Aug. 29, 1911.

Application filed November 17, 1910. Serial No. 592,843.

To all whom it may concern:

Be it known that I, EDGAR S. GARDNER, a citizen of the United States, residing at Acquackanonck, county of Passaic, State 5 of New Jersey, have invented certain new and useful Improvements in Filament-Mounting, of which the following is a specification.

My invention relates to filament mounting, and its object is an improved mounting suitable for filaments and other conductors which possesses various desirable characteristics.

Among the advantages which may be secured in a mounting constructed according to my invention are: First, the reduction to a minimum of the liability of the conductor to breakage, so that the apparatus will be especially suited for service in which it is 10 subject to vibration and shocks; second, the easy application of the conductor to its supporting system; third, the mounting of a great length of conductor in a small space, and that without risk of short-circuiting; 15 fourth, an arrangement of lamp filaments which will give a good distribution of illumination.

Other advantages will hereinafter appear.

My invention is very useful in incandescent filament electric lamps, especially when the lamps are used under such severe conditions as obtain in car-lighting service. I have hereinafter particularly described a construction embodying it that is well 20 suited for this purpose and for such conditions of use, referring to the conductor as a filament and to the apparatus in which it is employed as a lamp; but I desire it to be understood that my invention can be otherwise carried out and applied within the scope of the appended claims. In incandescent lamps my invention may be employed with filaments of tantalum, tungsten, or any other material.

50 The accompanying drawing gives a perspective view of one embodiment of the invention, the same being shown as broken away from the globe and removed therefrom for clearness of illustration.

55 The filament system or mount here shown comprises a plurality of filament-carrying elements or arms of iron, nickel, copper, molybdenum or other suitable material (due regard being of course had in its selection to the material of the filament) having suit-

able filament-engaging portions and projecting from supporting means consisting of a member or standard S and a suitable member or base D to which said member or standard S is attached. For convenience 60 sake, the members S and D may be regarded as constituting a single supporting member M. The member or base D may conveniently be a fixed part of the general lamp structure,—and, in particular, the ordinary 65 glass stem through which the current-supply conductors l, l, are introduced into the lamp. As shown, the arms or carriers a, and c form suitably separated groups or sets A and C, respectively, and the additional 70 or supplemental carriers b are shown as of different lengths from the carriers a and c and as arranged intermediate the carriers a and c and forming an intermediate group or set B. With the exception of the 75 arms or carriers a₁ and a₃₁ of the group A formed by portions of the leading-in wires l, l extending within the lamp globe, the carrying elements are fused into glass enlargements or disks on the member S. As 80 intimated above, the filament-engaging portions of the various carriers do not preferably project equally from the standard S, those of the carriers of the outer groups A and C—which may for convenience be 85 termed the lowermost and uppermost groups or sets, respectively,—preferably projecting farther than the supplemental carriers b, as shown in the drawing. The hooks or eyes forming the engaging portions of alternate 90 supplemental carriers lie in planes a short distance apart and “face” away from one another (so that the alternate supplemental carriers might be regarded as constituting different sets); but it will be understood 95 that the engaging portions of the supplemental carriers may, if desired, all lie in the same plane, or that a plurality of entirely distinct groups of supplemental carrying elements or arms may be employed and that such groups may be arranged as far apart as desired and may face either away from one another or toward one another, etc.

On the supporting system the filament is 100 arranged in a plurality of lengths or sections f, f', f''. From its connection with the end 1 of the left-hand current lead which forms the carrier a₁, the filament, as shown, extends upward to the engaging portion 2 of a downward facing supplemental car- 110

rier b_2 , thence downward to a carrier a_3 of the group A, thence upward to a carrier c_4 of the group C, thence downward to an upward facing supplemental carrier b_5 , 5 thence upward to a carrier c_6 of the group C, thence downward to a carrier a_7 of the group A, thence upward to a downward facing supplemental carrier b_8 , etc.,—passing finally downward from the carrier c_{30} of the 10 group C to the carrier a_{31} of the group A formed by the right-hand current lead and being suitably connected thereto. It will be understood that the filament-engaging portions of the various arms or carriers may 15 conveniently have the form of open hooks while the filament is being applied to the supporting system and that such hooks may afterward be closed to form eyes.

The filament system, it will be observed, 20 comprises a plurality of filament sections of two sorts: First, sections f (shown as approximately vertical) extending between carriers of the groups A and C; and second, intermediate sections f' , f'' (which, as 25 shown, are more or less inclined and somewhat shorter than the vertical sections) extending between carriers of the groups A and B and the supplemental carriers c and in series between neighboring sections of the 30 first sort as regards the passage of current. The intermediate sections f' , f' , or f'' , f'' lying between adjacent sections of the first sort terminate at carriers of the same one of the groups A and B, and the intermediate 35 sections f' , f' and f'' , f'' on opposite sides of a section of the first sort terminate at carriers of different groups. It will be observed that in this arrangement neighboring sections are everywhere well separated and 40 contiguous sections diverge from one another a substantial amount at their junction, so that there is practically no risk of short-circuiting. Moreover, the change in direction of the filament at the carrier between contiguous sections is in every case very considerable, so that even though the filament be—as shown in the drawing—continuous at this point, such sections are almost entirely 45 independent of each other as regards behavior under shock or vibration and there is little tendency for two sections to vibrate or move in unison. This is especially true of contiguous intermediate sections as compared with what would be the case if the 50 filament, for example, extended from the lowermost carrier a_1 to the uppermost carrier c_4 , and then to the lowermost carrier a_3 , etc. With such an arrangement, contiguous intermediate 55 sections would differ in direction but little at 2 and would, if continuous, behave very much like a single long length and respond like such a length to every influence tending to set them in motion, so 60 that such an arrangement would not be so

good as the one shown in the drawing. There would, in fact, be greater slackness of the filament owing to the greater allowance that must be made for shrinkage in the long length, greater vibration, greater liability 70 of the filament to breakage when the conditions of service are at all severe, and a corresponding shorter average life for the lamp. The mount would, furthermore, be harder to construct, and the application of the filament to it would present greater difficulties. 75 In the arrangement shown, on the other hand, the strains placed upon the filament in consequence of vibration are reduced to a minimum and it is supported in the most 80 efficient manner. Furthermore, the shrinkage in any one section is comparatively small and there is little opportunity for this shrinkage to result in dragging the filament over its supports. 85

What I claim as new and desire to secure by Letters Patent of the United States, is,—

1. A filament mount comprising groups of filament carriers suitably spaced apart, supplemental carriers having their filament 90 engaging portions arranged intermediate said groups, and a plurality of filament sections mounted on said carriers, adjacent filament sections that extend between carriers of the said groups having in series between them sections that terminate at supplemental carriers and at carriers of the same one of said groups. 95

2. A filament mount comprising groups of filament carriers suitably spaced apart, 100 supplemental carriers having their filament engaging portions arranged intermediate said groups, and a plurality of filament sections mounted on said carriers, adjacent filament sections that extend between carriers of the said groups having in series between them intermediate sections that terminate at intermediate carriers and at carriers of the same one of said groups and intermediate sections lying on opposite sides 110 of a section that extends between carriers of the said groups terminating at carriers of different groups. 115

3. The combination with outer sets of carrying elements projecting from a suitable 120 supporting member and suitably spaced apart of an intermediate set of such elements projecting from said member and a conductor arranged upon the elements of said sets in a plurality of sections, some of 125 said sections extending from an element of one outer set to an element of the other, and adjacent sections of this character being connected by sections which extend from an element of the intermediate set to elements of the same outer set. 130

4. A filament mount comprising outer sets of carrying elements and an intermediate set, the elements of said intermediate set differing in length from the others, and a 135

filament arranged thereon in a plurality of sections, the sections which extend between an element of one outer set and an element of the other being connected by sections 5 which extend between elements of the intermediate set and elements of the same outer set, and the connection of adjacent sections which terminate at elements of the outer sets as aforesaid being effected at opposite 10 ends alternately.

5. A filament mount comprising a member having suitably separated groups of filament-carrying arms and arms intermediate 15 said groups radiating therefrom, the intermediate arms being shorter than those of said groups, and a plurality of filament sections arranged on the arms, sections which join one another at an intermediate arm joining other sections at arms of the same 20 one of the groups aforesaid.

6. A filament mount comprising a filament arranged in a plurality of sections of different lengths supported by suitable carriers radiating from a central member, adjacent 25 sections of equal length being short and making an acute angle with one another.

7. A filament mount comprising suitably separated groups of carrying elements and intermediate carrying elements, and a plurality 30 of filament sections arranged on such elements, adjacent sections which terminate at an intermediate element extending therefrom to elements of the same one of the aforesaid groups, and sections terminating 35 at adjacent intermediate elements extending to elements of different groups.

8. A filament mount comprising outer and intermediate sets of carriers suitably spaced apart and a filament arranged thereon in a 40 plurality of sections, sections which join one another at one of two adjacent intermediate carriers terminating at carriers of one outer set and sections which join one another at the other of the said intermediate carriers terminating at carriers of the 45 other outer set.

9. A filament mount comprising two suitably separated sets of filament carriers projecting from a suitable supporting member and shorter supplemental carriers, and a plurality 50 of filament sections mounted on said carriers, certain filament sections extending between elements of the sets aforesaid, and intermediate sections in series between adjacent sections of this character 55 extending from one of the shorter carriers to carriers of the same one of the sets aforesaid.

10. A filament mount comprising two suitably separated sets of filament carriers radiating from a suitable supporting member and additional filament carriers shorter than those of the sets aforesaid, and a filament 60 mounted on said carriers comprising a plurality of sections extending between carriers 65 of said sets and also sections extending between said short carriers and carriers of said sets, sections which terminate at the same short carrier extending to carriers of the same one of the sets aforesaid, and sections 70 of this description that lie on opposite sides of a section which terminates at carriers of the said sets aforesaid extending to carriers of different ones of the sets aforesaid.

11. The combination with two suitably separated groups of carriers projecting from suitable supporting means and supplemental carriers projecting therefrom a less distance than those of said groups of a plurality of 75 conductor sections mounted on said carriers, sections which terminate at one of said supplemental carriers extending therefrom to carriers belonging to the same one of said groups.

In witness whereof, I have hereunto set my hand this 14th day of November, 1910.

EDGAR S. GARDNER.
